UNITED STATES PATENT OFFICE.

CHARLES SONNEBORN, OF WEST PITTSBURG, PENNSYLVANIA, ASSIGNOR TO PRESSED METAL RADIATOR COMPANY, OF PITTSBURGH, PENNSYLVANIA, A CORPORATION OF PENNSYLVANIA.

FORMING-DIES.

1,149,694.

Specification of Letters Patent.

Patented Aug. 10, 1915.

Application filed April 1, 1914. Serial No. 828,859.

To all whom it may concern:

Be it known that I, CHARLES SONNEBORN, a resident of West Pittsburg, in the county of Lawrence and State of Pennsylvania, 5 have invented a new and useful Improvement in Forming-Dies, of which the following is a specification.

This invention relates to dies for forming or shaping sheet metal articles.

10 The object of the invention is to provide dies for this purpose by means of which the articles can be very accurately shaped or formed, which are adjustable so as to adapt them for forming similar articles of different sizes, in which the various parts of the die are formed in separate pieces so that each can be accurately shaped, and dies in which the wearing parts can be readily replaced when worn.

20 Another object of the invention is to provide an improved holding and stripping device which may be readily adjusted for different sizes and shapes of article and in which the wearing parts may be readily replaced when worn.

In the drawings the invention is shown embodied in dies for forming sections of sheet metal radiators, but obviously the principle of construction of the dies may be 30 adapted for forming various articles.

In the accompanying drawings, Figure 1 is a face view of the bottom or male die; Fig. 2 is a similar view of the top or female die; Fig. 3 is a longitudinal section 35 through the bottom die on the line 3—3, Fig. 1; Fig. 4 is a vertical longitudinal section through the top die on the line 4—4, Fig. 2; and Fig. 5 is a transverse vertical section through the two dies on the 40 line 5—5, Figs. 3 and 4, and also showing the cushioning devices for the stripping ring.

The dies illustrated are adapted to be actuated by any suitable press, the bottom die 45 being suitably secured to the frame or bed plate of the press and the top die being carried by the vertically movable platen or press head. The means for securing these dies to the press bed and platen may be varied within wide limits. Both the top and bottom dies are of sectional or built up construction as hereinafter described.

The bottom die 1 comprises a pair of end sections or pieces 2 and one or more intermediate pieces or sections 3, depending

upon the length of the article being formed. By moving the end sections farther apart and interposing between the same a larger number of intermediate sections, or an intermediate section of greater length, the 60 die can be increased in length within limits to the desired extent.

Each end section 2 comprises a base portion 4 and a face or forming portion 5, the latter resting upon the base portion and being secured thereto by suitable means, such as the tap bolts 6 extending upwardly through holes in the base portion 4. Lateral movement of these two portions with reference to each other is prevented by 70 guide members 7 accurately fitting in registering grooves formed respectively in the top face of base member 4 and the bottom face of face member 5, and preferably secured by means of tap bolts to the base 75 member 4. The face member 5 is provided on its upper face with projections and protuberances so as to give the proper configuration to the article being pressed, the drawings showing the same provided with a plurality of longitudinally extending curved projecting portions 8 with intermediate depressions 9, but obviously the configuration may be varied within wide limits. Each of the end portions is also provided substantially at its longitudinal central line with a circular depression 10 in which fits a boss 11, being secured therein by tap bolts 12 extending upwardly through the member 4, and serving to press bosses in the sheet 90 metal article at both ends thereof, such for instance as the pipe connecting bosses of sheet metal radiators. By having these boss members 11 removable they can be readily replaced in case of excessive wear, or when 95 it is desired to change the height to which the boss is pressed out.

The intermediate member or members comprise a lower or base portion 4^a and a top or face member 5^a, these parts being secured together in the same manner as the parts 4 and 5 of the end sections, namely, by tap bolts 6^a, and being registered with the end members by means of the strips or guides 7. The top face of the member 5^a 100 of each intermediate section is provided with projections and depressions to match with the configuration of the end sections. When adapted for forming sheet metal radiator sections these intermediate portions are pro- 110

vided with the longitudinally extending projections 8^a and depressions 9^a which aline with and match with the parts 8 and 9 of the end sections.

- 5 The several sections of the base portion are secured to a suitable base or bolster plate 15, which is provided with a longitudinal groove or depression 16 of just the width of the die sections, so that said die sections 10 are held by this bolster plate against relative lateral movement. This bolster plate is secured to the bed or frame 60 of the press by suitable means, such as bolts 18 projecting down through holes in the base or bolster 15 plate into the frame. Said base or bolster plate is also provided with holes for receiving tap bolts 19 which extend up into the base members 4, 4^a, to secure the latter to said bolster plate.
- 20 Surrounding the sections of the bottom die and serving as a means to secure them together, is a suitable frame or "ring," the same comprising side bars or pieces 20 and end members or pieces 21. The end pieces 25 or members 21 fit between the ends of the side pieces 20, and are provided on their ends with tenons or tongues 22 fitting into grooves 23 formed in the inner faces of the side members 20, and said end members are 30 secured in place between the side members by means of strong cross bolts 24 extending through holes 25 in the side members and corresponding holes in the end members. These bolts serve to clamp the frame members together and form substantially a rectangular frame or "ring" surrounding the die sections. The inner faces of the frame members 21 are curved to the contour of the end sections 2 of the die so as to accurately fit the latter. In order to adapt the frame or "ring" to dies of various sizes the side members are provided with a series of holes 25 through any pair of which the bolts 24 may be inserted to clamp the end members 21 in any of the positions permitted by the spacing of the holes 25, to form a frame to fit built up dies having any desired number of intermediate sections 4^a. The end members 21 are further secured to 50 the side members by means of dowel pins 27 extending through the side members and entering the ends of the end members.

The top faces of the side members 20 are provided with rabbets 28, and the top faces 35 of the end members are provided with similar rabbets 29 for receiving respectively the side wearing plates 30 and end wearing plates 31, which are secured to said side and end pieces by means of tap bolts 32 extending up through holes in the side and end pieces and entering tap holes in said plates. Said wearing plates may be reversed end for end and side for side to utilize all available edges as they wear out.

55 The frame or ring is movable vertically

with respect to the lower die member and acts in conjunction with the upper die member to hold the sheet or plate perfectly flat or level while it is being shaped to prevent wrinkling or buckling, and also acts as a stripper member to eject the formed article from the lower die at the conclusion of the shaping operation. As shown the ring or frame is supported on the upper ends of a series of short pins 61 slidable in holes 62 75 in the frame 60 and bolster plate 15 and which rest on the upper ends of rods 63, which in turn are supported by a common pressure plate 64. Plate 64 is supported by a series of yielding or spring members, such as the rubber blocks 65 carried by washers or seats 66 held by nuts 67 and filling tubes 68 on rods 69 threaded into the frame 60. By turning the nuts 67 the upward pressure against the stripper ring may be increased 80 or diminished, and its position may be adjusted by inserting loose pins 61 or filling tubes 68 of the necessary length, as will be readily understood.

The top or female die comprises the two 90 end sections 34 and one or more intermediate sections 35. The end sections 34 are provided on their bottom or working faces with the reversed configurations of the end sections 2 of the bottom die, to-wit, with longitudinally extending depressions 38 corresponding to the projections 8 of the bottom die 2 and intermediate elevations 39 corresponding to the depressions 9 of the lower die. These end sections are also provided with circular seats 40 for receiving the female bossing member 41 corresponding to male bossing member 11 and which are secured to the end sections 6 by means of tap bolts 42. These end sections are also 100 provided with a seat extending around the embossing or forming portions 38, 39 for receiving the wearing members which extend around the outer edge of the die face, or in other words, form the outer boundary of 110 the die face proper. These wearing members comprise a straight end portion 43, curved corner portions 43^a and straight longitudinal portions 44, all of which are secured to the end section 36 by suitable tap 115 bolts 45. The projecting portions 39 of the female die are also preferably formed in separate renewable pieces, being so shown in the drawings and seated in a suitable groove or depression and secured thereto by tap 120 bolts 46.

The intermediate female die members 35 are provided on their working faces with longitudinal depressions 38^a corresponding to the depressions 38 of the end sections 34, 125 and with longitudinally elevated portions 39^a corresponding to the portions 39 of the end section 34, which portions 39 are also separate wearing bars seated in suitable grooves in members 35 and secured therein 130

by tap bolts 46^a. The wearing members 44 of the end sections are continued in these intermediate sections, being indicated at 44^a, and seated in suitable grooves in the faces of 5 the intermediate sections and secured therein by tap bolts 45^a.

The end sections 34 and intermediate sections 35 are provided in their lower faces with alining grooves 48, and are adapted to 10 be secured to a suitable base or bolster plate 49, the latter of which is provided with a longitudinal groove 50, said alining groove being adapted to receive a guide bar 51. The base or bolster plate 49 is provided with 15 holes 52 for receiving bolts 53 extending up from the die sections 34 and 35 respectively into the bolster plate for securing the section in plate.

The end sections 34 of the top die are provided on their side portions with wings 54 which are provided with openings or 20 grooves 55 for receiving the longitudinal tie rods or bolts 56, for tying the several die sections firmly together. The top and bottom dies are caused to reciprocate in exact 25 alinement with each other by any suitable means or mechanism, as will be readily understood.

The dies described are of sectional construction so that they can be varied to form 30 pressed sections of various lengths, by merely taking out certain one or ones of the intermediate sections and replacing them by intermediate sections of different length, or 35 leaving the intermediate sections out entirely. The sectional construction also adapts the wearing portions to be renewed as necessary, and also adapts the working faces to be replaced by working faces of a 40 different configuration. The manner of building up the dies enables them to be very accurately constructed so as to produce pressed sections of absolutely uniform and interchangeable shape.

45 It is obvious that the particular construction of dies described may be adapted to form pressed articles of a variety of kinds and forms.

What I claim is:—

50 1. A forming die comprising end sections and one or more changeable intermediate sections having working surfaces matching those of the end sections, a base plate, and interlocking guiding means engaging registering grooves in the base plate and in the back faces of the end and intermediate sections.

60 2. A forming die comprising end sections and one or more changeable intermediate sections having curved working surfaces matching the working surfaces of the end sections, said sections comprising a base and working face portions, and interlocking connections between the same.

65 3. A forming die comprising end sections

and one or more changeable intermediate sections having working surfaces matching those of the end sections, each of said sections comprising a base and a working face portion, and an interlocking guide strip engaging registering grooves in the top face of the base portion and the back faces of the working face portions. 70

4. A forming die comprising end sections and one or more changeable intermediate sections having working surfaces matching those of the end sections, some of said sections being provided with a seat, and separate embossing members secured to said seat. 75

5. A forming die comprising end sections and one or more changeable intermediate sections having working surfaces matching those of the end sections, longitudinal die members located interiorly of said die, a frame surrounding said sections and comprising side bars and end pieces between said side bars, and means for securing said end pieces in various positions. 85

6. A forming die comprising end sections and one or more changeable intermediate sections having curved working surfaces matching the working surfaces of the end sections, intermatching wear plates on said end and intermediate sections arranged to project normally beyond the working surfaces of said sections, and means for securing together said end and intermediate sections. 90

7. A forming die comprising end sections and one or more changeable intermediate sections having working surfaces matching those of the end sections, a frame surrounding said sections and comprising side bars grooved on their facing sides, end pieces 100 provided with tenon ends entering the grooves in said side bars, and means for securing said end pieces to said side bars in various positions to form a continuous structure with the one or more intermediate sections. 110

8. A forming die comprising end sections and one or more changeable intermediate sections having working surfaces matching those of the end sections, said end and intermediate sections being provided with seats, those of the intermediate sections alining with those of the end sections, and working or wear members secure in said seats and projecting above the normal faces of the 115 dies. 120

9. A forming die comprising end sections and one or more changeable intermediate sections having curved working surfaces matching those of the end sections, wear members secured in seats on the end and intermediate sections and extending peripherally of the die, a frame surrounding said end and intermediate sections, a bolster plate to which said sections are secured, a yield- 125 130

ing pressure plate, and pins supported by said plate and at their ends engaging said frame.

10. A forming die comprising end sections and one or more changeable intermediate sections having surfaces matching those of the end sections, a frame surrounding said sections, a bolster plate to which said sections are secured, a yielding pressure plate,

and pins supported by said plate and at 16 their ends engaging said frame.

In testimony whereof, I have hereunto set my hand.

CHARLES SONNEBORN.
